Des. 211,574
Patented July 2, 1968

211,574

PHOTOELECTRIC COLORIMETER

Delmar F. Macaulay and Elliott E. Blank, Midland, Mich.,
assignors to The Dow Chemical Company, Midland,
Mich., a corporation of Delaware

Filed Apr. 4, 1967, Ser. No. 6,512

Term of patent 14 years

(Cl. D16—2)

Fig. 4

Fig. 3

Fig. 5

FIGURE 1 is an isometric view of a photoelectric colorimeter, showing our new design;

FIGURE 2 is a front elevational view thereof;

FIGURE 3 is a side elevational view thereof;

FIGURE 4 is a top view thereof; and

FIGURE 5 is a rear view thereof.

The dominant features of our design reside in the portions shown in full lines. The side of the photoelectric colorimeter not shown is the mirror image of the side shown.

We claim:

The ornamental design for a photoelectric colorimeter, substantially as shown and described.
